UNITED STATES PATENT OFFICE.

LUTHER M. MOREHOUSE, OF FLY MOUNTAIN, NEW YORK, ASSIGNOR OF ONE-HALF TO CHARLES STRAWN, OF SAME PLACE.

CASTER.

SPECIFICATION forming part of Letters Patent No. 250,634, dated December 6, 1881.

Application filed August 11, 1881. (Model.)

To all whom it may concern:

Be it known that I, L. M. MOREHOUSE, a citizen of the United States of America, residing at Fly Mountain, in the county of Ulster and State of New York, have invented certain new and useful Improvements in Casters; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification, and in which—

15 Figure 1 is a rear elevation of my improved stove-leg caster. Fig. 2 is a side view thereof, showing the caster in an elevated position, and Fig. 3 is a sectional view thereof.

This invention has relation to improvements 20 in casters particularly adapted for stoves, it being capable of allowing the leg to rest upon the floor when the stove has been rolled to its destination, and the ready adjustment of the caster to elevate the leg and bring the caster 25 in bearing contact with the floor preparatory to moving the stove.

The nature of this invention consists in combining with the sliding spindle of the caster, having a disk or bracket, a concentrically- 30 pivoted lever, with its lower end adapted to rest upon the disk or bracket of the caster, substantially as hereinaftermore fully set forth.

In carrying out my invention I employ, in connection with the sliding caster-spindle A, 35 having a disk or bracket, a, to the under side of which is hung the wheel or wheels b, a lever, B, of a cylindrical shape, and open at one side, as at c, to permit it to receive the spindle A. The lever B is pivoted to the web of 40 the leg C, and being open at one side, as at c, it is capable of being turned up, as seen in Fig.

2, freeing its lower end from the bracket a, when the leg C will be permitted to descend and rest upon the floor or other support. The lever B may, for convenience of operation, have 45 a handle, B', attached to it.

The caster, when in a lowered position, is below the stove-leg, and is thus brought in a bearing contact with the floor, when the stove may be rolled or moved to its destination. After this, by releasing the lever B from the caster-disk a, the stove-leg can be readily lowered to the floor, and thus take the strain and weight off the lever. By this construction of parts, it will be noticed that the pressure is distributed upon the spindle and wheels when the lever is in use, and it being concentrically pivoted with the spindle the lever is not liable, as might arise were it otherwise arranged, to be tripped off the spindle or caster-disk. The 50 pressure is removed from the pivotal points of the lever B by causing its upper bifurcated ends to move in contact or abut against shoulders e e, formed upon the web of the stove-leg. 55

The web may, to be applied to a stove-leg of 60 the ordinary construction, be made of wood and suitably affixed to the leg. Usually the web is cast with the stove-leg.

Having thus fully described my invention, I claim and desire to secure by Letters Patent— 70

In a stove-leg caster, the combination, with the sliding caster-spindle, having the caster disk or bracket a, and webbed stove-leg C, of the lever B, cylindrical in form, and open at one side, as at c, and concentrically pivoted with 75 the spindle, substantially as set forth.

In testimony whereof I affix my signature in presence of two witnesses.

LUTHER M. MOREHOUSE.
